MATERIAL LIFTING AND TRANSFERRING APPARATUS

Henry E. Miller, Columbus, Ohio

Application September 21, 1951, Serial No. 247,643

3 Claims. (Cl. 212—11)

1

This invention relates generally to material handling, lifting and transferring apparatus, having particular reference to apparatus adapted for the handling of stacked materials, such as building brick or block, whereby to enable such materials to be moved from place to place in an economical, rapid and convenient manner.

An object of the invention is to provide apparatus capable of handling building brick, block or other products in unit groups, piles or stacks, so that a comparatively large number of such products, while maintained in orderly formation, may be transferred from one location to another and without disturbing their relative order.

Another object of the invention is to provide a product carrier which is suspended from and operates in conjunction with an overhead crane mechanism, the latter being so constructed as to provide means for raising and lowering the carrier and products supported thereon and selectively and bodily moving the same along pre-scribed longitudinal and transverse paths of travel.

A further object of the invention is to provide portable product-lifting and transferring apparatus employing a carrier having a horizontal bottom member and an upright back member, and wherein said back member carries at each side thereof upper and lower sets of spaced guides which embrace a rigid guide frame carried by and depending vertically from a longitudinally and transversely movable overhead crane mechanism, the latter including a power-actuated hoist having a cable connected with said carrier, whereby to effect movement of said carrier in conjunction with said crane mechanism as well as vertical movement of the carrier with respect to said guide frame.

Another object of the invention resides in a brick-setter or lifting mechanism which includes a fork-type carrier having a horizontal bottom member joined with a vertical back member, and wherein the upper portion of said back member is provided with a forwardly and horizontally projecting cable-attaching arm disposed above the horizontal bottom member of the carrier and adapted for connection with the lower end of a crane-carried raising and lowering mechanism.

Other objects of the invention will be more fully realized from a perusal of the following detailed description setting forth a single preferred embodiment of my improved product-handling apparatus, the latter being illustrated in the accompanying drawings, wherein:

2

Fig. 1 is a top plan view of the product-handling apparatus forming the present invention;

Fig. 2 is a side elevational view thereof;

Fig. 3 is a front elevational view;

Fig. 4 is a vertical sectional view disclosing the rollers carried by the back member of the fork-type carrier of the apparatus, and illustrating the position of such rollers with respect to a depending crane-carried guide frame;

Fig. 5 is a horizontal sectional view taken on the plane indicated by the line 5—5 of Fig. 4.

Referring more particularly to the drawings, the numeral 1 designates a stationary frame composed preferably of structural steel members disposed to provide a pair of elevated, substantially horizontally extending girders 10. In this instance, there is mounted on the girders a pair of track rails 11, the latter being arranged in a horizontal plane and extend longitudinally of the supporting frame. The supporting frame has been shown as carried by ground or floor structure, although it will be apparent that, if desired, the girders may be suspended from any suitable type of overhead means, not shown, such as the roof structure of a building.

Arranged for rolling movement on the rails 11 longitudinally of the frame is the primary or lower carriage 12 of a crane mechanism. In this instance, the carriage supports for rotation a pair of parallel transversely extending axles 13, the latter carrying wheels 14 which ride on the heads of the rails 11. Movement may be imparted to the wheels from an electric motor 15, or its equivalent, which has been shown as being mounted on one side of the carriage 12. Preferably, the drive shaft of the motor 15 operates a belt wheel around which passes an endless belt 16, leading to another belt wheel which is carried by one of the axles 13, causing rotation of that axle either in a forward or rearward direction to propel the primary carriage along the frame structure, as desired. Power may be imparted to both of the carriage axles 13 by means of an endless chain or belt 17, which

40 passes around sprockets or belt wheels fixed to aligned ends of said axles.

45 Joining the wheel-enveloping side frames, shown at 18, of the primary carriage are transversely extending rail-forming members 19.

50 Mounted for rolling movement on these members is the upper or secondary carriage 20 of the crane. This carriage comprises a substantially rectangular frame 21 of smaller dimensions than the frame of the lower carriage 12, as shown 55 more particularly in Fig. 1. The frame 21 sup-

ports for rotation a pair of spaced parallel axles 22, and carried by the end regions of these axles are wheels 23 having flanged engagement with the rail members 19 of the lower carriage.

To propel the upper carriage on the rail members of the lower carriage in a back and forth manner transversely of said lower carriage, the frame 21 is provided with an electric motor 24, or its equivalent. The shaft of this motor, through a belt, indicated at 25, drives one of the axles 22, power of the motor being applied simultaneously to said axles by an endless chain or belt, shown at 26, passing around belt wheels or sprockets fixed in aligned relationship to the axles 22.

Also mounted on the upper carriage is a product carrier raising and lowering device, such as the power-driven hoist mechanism, indicated at H. This mechanism may be formed to comprise an electric motor 27, which, through a speed-reducing mechanism, indicated generally at 28, drives a drum 29 on which is spooled a cable 30. The latter includes a depending end which is preferably fastened as at 31 to a forwardly projecting arm 32 mounted in connection with the upper end of a product carrier 33.

Preferably, this carrier comprises an L-shaped structure embodying a bottom section 34 and a perpendicularly disposed and upstanding back section 35, the bottom and back sections being composed normally of a plurality of spaced parallel members rigidly united by transversely extending cross bars 36. The bottom 34 of the carrier is formed so that it may readily be inserted beneath a pile of stacked products, such, for example, as passing between spaced courses of a pile of building brick, whereby to deposit the brick on the bottom of the carrier. Through the provision of the back section 35 a means is provided to sustain the brick or other products on the carrier, permitting of the bodily transportation of such brick or products through manipulation of the overhead crane mechanism. It will be noted that the arm 32 overhangs the top and central portions of the carrier, so that the elevating forces of the hoist mechanism H will pass substantially through the pile of products positioned on the carrier.

Depending from the upper or secondary carriage 20 is a rigid guide frame which may consist of a pair of columns or posts constituting the frame shown at 37, the latter being used to support and guide the carrier 33 in its vertical movement.

To this end, the carrier is provided at each side of the back section 35 thereof, with a pair of fixed U-shaped brackets, indicated at 38 and 38', which are disposed in vertically spaced relationship. The lower set of brackets 38' carry a pair of rollers 39 which embrace the vertical guide members of the frame 37, as shown more particularly in Fig. 4. The upper set of brackets 38 are formed so that each thereof carries a stirrup 40. Each of these stirrups receives a pair of spaced guide rolls 41, which preferably are of spool-shaped configuration to conform with the circular cross-sectional configuration of the frame posts 37. The ends of the rolls 41 are provided with journalling axles 42. These axles are received in bearing openings 43 provided in the stirrups 40, while the ends of the axles project through elongated slots 44 formed in the brackets 48.

To move the stirrups back and forth, whereby to bodily tilt the carrier and to cause the same

to assume desired operating positions, as indicated by the full and broken lines disclosed in Fig. 4, each of the stirrups 40 has connected therewith one end of a screw shaft 45, which is turnable in a threaded opening provided in the closed leg of each stirrup. Also carried by the screw shafts 45 is a sprocket wheel 46, around which passes an endless chain 47, so that the sprocket 46 of both the brackets 38 will be rotated in unison with its companion sprocket. A hand crank 48 may be used for rotating one of said screw shafts. Of course, other operating means may be provided. If desired, the upper carriage may be formed at the rear thereof with a depending seat-carrying frame 49. An operator's seat may be secured to the lower end of this frame in a control zone. From this zone, the operator of the machine may regulate the movements of the primary and secondary carriages 20 on their supporting tracks through control of the operation of the driving motors, as well as the operation of the hoist mechanism in raising and lowering the product carrier.

It will be understood that my improved apparatus is adapted for lifting, handling and conveying many different types of products and installed either in indoor or outdoor locations. The apparatus may be used advantageously in warehouses, or in connection with the loading and unloading of ceramic products entering or leaving firing or drying kilns. The bottom section of the carrier of the present invention may readily extend beneath a slab or pallet supporting on the top surface thereof a stack comprising, for example, spaced brick arranged in vertically superposed courses, whereby the brick may be handled in a unitary manner without loss in the form or arrangement thereof. The arrangement enables a stack of brick to be bodily handled, as in placing the same on kiln cars, or in removing fired stacks of brick from the car platforms. The apparatus minimizes the time required in effecting such operations, and dispenses with the use of conventional self-propelled lift trucks.

By adjusting the slidable stirrups 40, the carrier turns bodily about horizontal axes afforded by the lower rollers 39 of the brackets 38', adapting the carrier to different positions of product retention as disclosed in Fig. 4. The spool rolls 41 prevent lateral movement of the carrier by reason of their engagement with the tubular guide frame members.

While the preferred form of the invention has been set forth in considerable detail, nevertheless it will be understood that the construction is subject to certain variations or modifications without departing from the spirit and scope thereof as set forth in the following claims.

I claim:

1. In product-lifting and conveying apparatus, a crane-carried vertically disposed guide frame, a product carrier having a horizontal bottom section and a vertical back section, said back section being disposed laterally of and at the front of said guide frame, upper and lower bracket devices projecting rigidly and rearwardly from the back section of said carrier, antifriction means rotatably carried by said devices in engagement with said guide frame, and means for shifting the operating positions of the antifriction means provided in the upper of said devices relative to the position of the antifriction means in the lower of said devices, whereby to vary the angularity of the carrier with respect to said guide frame.
2. In product-lifting and conveying apparatus,

a crane-carried guide frame, said frame including a pair of transversely spaced vertically extending and parallel posts, a product carrier having a horizontal bottom section and a vertical back section, said back section being disposed laterally of and at the front of said guide frame, upper and lower bracket devices projecting rigidly and rearwardly from the back section of said carrier at each side thereof and slidably embracing said frame posts, spool-shaped rolls carried by the lower set of said devices in engagement with said posts, a yoke slidably mounted in each of the upper of said bracket devices, a pair of spool-shaped rolls carried by each of said yokes and disposed in engagement with said posts, and means for adjusting said yokes longitudinally relative to said upper devices to control the angularity of said carrier with respect to the vertical plane of said posts.

3. Product-lifting and conveying apparatus as specified in claim 2 and further characterized by the provision of a crane-carried power-actuated hoist mechanism connected with said carrier for raising and lowering the same with respect to said guide frame.

HENRY E. MILLER.
